(57) **CLAIM**

We claim the ornamental design for a magnetic resonance imaging (MRI) patient transporter, as shown and described.

DESCRIPTION

FIG. 1 is a front perspective view of a magnetic resonance imaging (MRI) patient transporter, showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right elevation view thereof.

The broken lines in the drawings depict portions of the magnetic resonance imaging (MRI) patient transporter that form no part of the claimed design.
